UNITED STATES PATENT OFFICE.

DORR MILLER, OF TOLEDO, OHIO.

WINDOW-REGULATING DEVICE.

Application filed April 11, 1923. Serial No. 631,275.

To all whom it may concern:

Be it known that I, DORR MILLER, a citizen of the United States, and a resident of Toledo, in the county of Lucas and State of Ohio, have invented certain new and useful Improvements in Window-Regulating Devices, of which the following is a specification.

This invention relates to window regulators and consists of an improved window operating mechanism particularly adapted for use in automobile body construction of the limousine or closed body types. The device of the present invention is designed with the particular object of producing a regulating mechanism possessing important advantages over the mechanisms at present used and which will be sturdy and economical of construction and more efficient in its operation.

Important and valuable features of my improved regulator include an improved construction and arrangement of the parts which allows of the ready application of the device to the door or body construction where its use is desired with the minimum of interference with other structure and thereby avoiding to a large degree weakening other members of the body construction, as for example the lock board of a door structure when mounted thereon. The improved mechanism is of a design which allows of its operation manually from a plurality of conveniently located points thereby permitting a desirable choice of location of the operating handle which may thus be determined with relation to the location of the seating arrangement of varied bodied designs. It is of few and simple parts which may be reassembled upon a suitable supporting plate and thereby adapted for unit installation and the parts thereof are of a size and arrangement which permits of generally universal application to the commercial narrow and wide door standards of the industry and likewise for operating the glass of the body rear quarter as the mechanism is compact and adaptable to short or long lifts as the circumstances require. In addition my improved mechanism by reason of its improved manner of operation allows of liberal tolerances and in consequence economy in its manufacture as delicate parts and accurate adjustments are not essential to its proper operation. It is moreover designed to support and apply the lift-

ing forces to the underside and centrally of the window glass, thereby to avoid the tendency of the glass binding within its guiding channels or slots. My improved mechanism further provides for the desirable counter-balancing of the window pane in a manner to insure ease of operation and smoothness in its action.

Further features and advantages of my improved regulator mechanism will be more fully understood by reference to the accompanying drawings illustrating a desirable embodiment thereof and wherein like reference numerals are employed to designate the corresponding parts in the several views.

In the drawings:

Fig. 1 is a view in side elevation illustrating the regulator mechanism of my invention as applied to an automobile door structure for operating the glass thereof.

Fig. 2 is a vertical cross-sectional view thereof.

Fig. 3 is a view corresponding to Fig. 1 with the parts shown in the opposite extreme position as assumed when the glass is fully lowered.

Fig. 4 is a view in side elevation illustrating a modification in the location of the operating lever.

In the approved embodiment of the features of my invention as herein disclosed the mechanism is illustrated as applied to an automobile door structure for operating the window or glass thereof. The door is shown composed of the frame members 1, the vertical members thereof being provided with the usual vertical and inwardly directed guide slots 2 providing guide-way within which is received the window glass 3 adapted to be moved vertically for opening and closing the window aperture in the usual manner. The glass is supported at its lower edge within a channel member 4 and the door is provided with the usual cross-bracing member or lock board 5 connecting the opposite vertical frame members.

The operating parts of my improved window regulating device are desirably mounted upon a supporting plate 6, which, as shown, is a flat plate of suitable form and is attached to the lock board 5 of the door by means of the securing screws 7-7. The operating parts comprise a window regulating lever and toggle actuating links or levers therefor designed to be movable above

and below the center bearing in their operating movement in a manner to transmit a substantial or extended movement to the operating end of the operating lever, which 5 will be vertical and rectilinear in direction.

Of the operating parts, 10 is the operating lever having an arm extension provided with a pin 11 fitted within the elongated slot 12 of connecting member 13 depending 10 from and attached to the supporting channel 4 carrying the glass to be operated. The lever 10 is fulcrumed upon a pin 15 supported upon the outer extremity of a lifting bell-crank lever 16 having a rearwardly extended arm 17 rigidly connected thereto and keyed upon a bearing pin or spindle 18 suitably journalled and supported by the plate 6. The operating lever 10 at one end is pivotally connected at 20 to 15 a toggle arm 21 which at its center portion is provided with a fulcrum pin or roller 22 fitted within the horizontally extended and elongated slot 23 formed in the supporting plate 6, as shown. The opposite 20 end of the toggle arm 21 is pivotally connected by a pin 25 with an arm 26 of a bell-crank lever having a second arm 27 and pivotally supported upon the center bearing spindle or pin 18, as shown. Upper and 25 lower equalizing arms 29 and 30 are arranged, as shown, each pivotally supported at its outer end upon a fulcrum pin or roller 31 fitted within a longitudinally extended slot 32 formed in the supporting plate 6. 30 The inner ends of equalizing arms 29 and 30 are pivotally connected respectively to the arms 17 and 27 of the bell-crank levers by means of the pivotal bearing pins 34 and 35.

40 As will be noted the horizontally extended guiding slots 23 and 32 are formed in the plate 6 in the horizontal plane of the axis of the bearing pin or spindle 18 which for distinction is hereinafter referred to as the "center bearing." The arms 17 and 45 27 of the respective bell-crank levers are arranged in right angular relation to their complementary arms 16 and 26 and are reversely disposed in symmetrical angular relation to the horizontal plane of the center bearing. The pivotal connections 34 and 35 are likewise symmetrically positioned at 50 opposite sides of the horizontal line through the center bearing, with the equalizing arms 55 reversely and symmetrically positioned above and below this horizontal plane. The bell-crank lever arms 16 and 26, the operating lever 10 and the toggle arm 21 form an articulated rectangular toggle structure the 60 opposite members of which are parallel and of equal length. Also, as will be noted by reference to Fig. 1, the upwardly extended portion of the operating lever 10 from the center of pivot 15 to the center of the 65 pivot 11 corresponds in length to the dis-

tance between the center of pivot 15 to the center bearing or axis of the center bearing spindle 18.

As shown in Figs. 1, 2 and 3 the manipulating means for the operating levers consists of a crank-handle or lever 40 fixed upon the external end of a shaft 41 suitably journalled upon the supporting plate 6 and having secured upon its inner end portion a pinion 42, the teeth of which mesh with a gear segment 44 supported upon an extension of the bell-crank arm 17 and at its lower end upon an arm 45 which is an extension of the lever 16. Thus the gear segment is rigidly supported by the lifting lever 16 by means of its rigid arm extensions whereby the gear segment 44 rotates about the center bearing 18 and is accordingly formed concentric therewith. Turning of the crank 40 will effect the movement of the operating levers to transmit the movement to the glass 3 for raising and lowering of the latter.

In the operation from the extreme elevated position, as indicated in Fig. 1, the respective levers will move in the directions as indicated by the arrows and simultaneously the sliding fulcrums 22 and 31 will move horizontally within the slotted guideways until the parts assume the final position, as indicated in Fig. 3, wherein the glass is shown fully lowered. In this movement the operating end of the operating lever 10, as defined by the connecting or coupling pin 11 will move vertically with a rectilinear movement by reason of the toggle action of the rectangular articulated structure composed of members 10, 16, 21 and 26 during which movement the pivotal points 15, 20 and 25 will pass center with relation to the horizontal plane through the center bearing 18. During the operating movement the symmetrical angular relations of the links are maintained under the controlling influence of the sliding fulcrums, which as indicated, are guided to move in a rectilinear plane. As otherwise expressed with relation to the articulated rectangular structure, composed of members 10, 16, 21 and 26 the center bearing 18 and sliding fulcrum 22 control the movement of the respective links whereby they will maintain a symmetrical relation at all times to the horizontal plane whereby the movement imparted to the coupling pin 11 will be rectilinear and vertical in direction.

The characteristics of the operating movement may perhaps be best understood when considered with respect to the vertical plane as defined by the line of travel of the pin 11. It will be noted with relation to this vertical plane that the lifting lever 16 and the operating lever extension, of a length equal thereto, conform to the two sides of a triangle which uniformly change their angu-

lar relation during their movement to reversal of position. In consequence, the operating connection or pivot 11 in its movement will define the base of the respective triangles completed by the two side members both above and below the central longitudinal plane and accordingly its path of movement is established as a straight line. This symmetrical movement of the angular members is insured by the controlling action of the fulcrum points 18 and 22 which are fixed with reference to the horizontal plane. It, therefore, occurs that the angular members are movable only in unison and in what may be termed a movable symmetrical relation to a fixed plane to produce a straight line or vertical operating movement. It will be noted that in the full past center movement in one direction as from the extreme upper to the extreme lower position of the glass 3 the fulcrum 22 will move from initial position indicated in Fig. 1 to the opposite end of the slot 23 and return to initial position as indicated in Fig. 3.

With the described construction I desirably associate suitable means for counter-balancing the weight of the glass and other moving parts and for this purpose is here shown a helical spring 50. This spring at its innermost coil is bent to a squared form and closely fitted to a squared portion 51 of the center bearing spindle 18 and the outer extremity of the spring is formed with a loop or hook portion 52 fitted to an extension of the pivot 25. With this arrangement the spring is assembled under tension, as indicated in Fig. 1, to exert a pressure in the direction tending to elevate the glass and to a degree to produce a counter-balancing effect. Incidental to this structure the tension of the spring may be readily varied to meet specific conditions by assembling the squared innermost coil thereof in varied positions upon the squared portion 51 of the center bearing.

While as disclosed in Figs. 1, 2 and 3 a segmental rack and lever operated pinion may be employed to manipulate my improved regulating device, and as will appear quite obvious from the construction other manipulating means may be employed therewith for the lever arrangement is susceptible to manipulation from differently located points. This offers a material advantage in permitting the location of the operating lever to be varied in accordance with the body seating arrangement. As illustrative thereof a hand lever or handle may be externally fixed to an extended portion of the fulcrum pin 31 to operate with a sliding movement to manipulate my improved device. As will be obvious this latter arrangement may be employed alone as the manipulating means or in conjunction with other means, as shown.

As further illustrated in Fig. 4 and in dotted lines in Fig. 2, my improved device may also be manipulated by a hand lever 61 fixed to an externally extended portion of the center bearing spindle 18. Also where this means is employed as the sole means of operation, as indicated in Fig. 4, and as will be understood, the segmental rack and pinion of Figs. 1 to 3 may be omitted together with the supporting arms therefor.

My improved mechanism as disclosed is of a type particularly well adapted for economy in manufacture and particularly adaptable to varied installations by reason of its compactness and as hereinbefore referred to is advantageous and economical in permitting substantially completed assembling of the operating parts at the point of manufacture thereby allowing installation as a unit by the body builders. The rectangular articulated lever structure is efficient in its operation and adapted to impart or transmit a long throw movement to the window with economy of structure by reason of the toggle action and pass center movement. This movement is moreover definitely controlled and guided by the movable fulcrum points whereby the operating end of the operating lever moves in a straight line which insures smoothness in its operation by avoiding lateral pressures. My improved structure as aforesaid is further advantageous in allowing for the varied positioning of the manipulating levers and the presence of the counter-balancing spring provides for the taking up of all lost motion in a manner which contributes to silence in operation.

Having described my invention I claim:

1. In a window regulator, in combination with a window member to be operated, articulated operating connections therefor comprising angularly disposed operating levers, movable fulcrum means to control the movement of said levers in symmetrical angular relation to a fixed plane for transmitting a rectilinear motion to the operated member, resilient means suitably connected to the operating connections to counter-balance the weight of the parts and means adapted for manually manipulating the operating connections.

2. In a window regulator, the combination of a window member to be operated, articulated operating connections therefor comprising angularly disposed operating levers, said operating levers being movable above and below center to extend the movement in reversed angular relation, means to actuate the levers and equalizing means connected to the operating levers at each side of the neutral plane to balance the operating pressures throughout the movement.

3. In a device of the character described,

- the combination of a movable member to be operated, of an articulated operating lever structure comprising reversely arranged bell-crank levers, toggle lever connections pivotally connecting one arm of each of the bell-crank levers, one of said connections having an operating lever extension connected to the movable member, means to control the movement of said levers in symmetrical angular relation to a fixed plane whereby a rectilinear movement is transmitted to the operated member, said bell-crank levers being movable past center to extend the movement in reversed angular relation and manipulating means comprising a segmental gear carried by one of the bell-crank levers, an operating pinion suitably journaled to mesh therewith and an externally arranged lever rotatably secured to the pinion.
4. In a device of the character described, the combination of a movable member to be operated, of an articulated operating lever structure comprising reversely arranged bell-crank levers, toggle lever connections pivotally connecting one arm of each of the bell-crank levers, one of said connections having an operating lever extension connected to the movable member, means to control the movement of said levers in symmetrical angular relation to a fixed plane whereby a rectilinear movement is transmitted to the operated member, said bell-crank levers being movable past center to extend the movement in reversed angular relation and manipulating means comprising a segmental gear carried by one of the bell-crank levers, an operating pinion suitably journaled to mesh therewith and an externally arranged lever rotatably secured to the pinion and a counter-balance spring connected to the respective bell-crank reversely and operative normally to impart a lifting pressure thereon to counter-balance the weight of the parts.
5. In a device of the character described, the combination with a movable member to be operated, of articulated operating connections therefor comprising angularly disposed operating levers, means to control the movement of said levers to transmit a rectilinear movement to the operated member, a supporting member providing bearing support for the operating connections whereby they are adapted for unit installation and said operating connections being arranged to allow for the application of a manipulating lever in varied position thereon, substantially as described.
6. In a device of the character described, the combination of a movable member to be operated, an articulated operating lever mechanism comprising reversely arranged bell-crank levers, toggle lever connections pivotally connected therewith to form the

rectangular toggle acting structure having a fixed bearing at one pivotal point and a movable fulcrum bearing in horizontal alignment therewith, one of the toggle levers having an operating extension connected to the member to be operated equalizing levers pivotally connected to a common pivotal bearing supported to be movable in the horizontal plane of the fixed bearing aforesaid, said equalizing levers being arranged respectively above and below said horizontal plane and pivotally connected to arms of the respective bell-crank levers and a hand lever suitably connected to the operating mechanism for manual manipulation thereof.

7. In a device of the character described, the combination of a movable member to be operated, an articulated operating lever mechanism comprising reversely arranged bell-crank levers, toggle lever connections pivotally connected therewith to form the rectangular toggle acting structure having a fixed bearing at one pivotal point and a movable fulcrum bearing in horizontal alignment therewith, one of the toggle levers having an operating extension connected to the member to be operated equalizing levers pivotally connected to a common pivotal bearing supported to be movable in a horizontal plane of the fixed bearing aforesaid, said equalizing levers being arranged respectively above and below said horizontal plane and pivotally connected to arms of the respective bell-crank levers and a hand lever suitably connected to the operating mechanism for manual manipulation thereof in a helical counter-balance spring connected respectively at its inner and outer ends to exert pressure upon the bell-crank levers in the direction tending to elevate the movable member, substantially as described.

8. In a device of the character described, the combination of a movable member to be operated, an articulated operating lever mechanism comprising reversely arranged bell-crank levers, toggle lever connections pivotally connected therewith to form the rectangular toggle acting structure having a fixed bearing at one pivotal point and a movable fulcrum bearing in horizontal alignment therewith, one of the toggle levers having an operating extension connected to the member to be operated equalizing levers pivotally connected to a common pivotal bearing supported to be movable in the horizontal plane of the fixed bearing aforesaid, said equalizing levers being arranged respectively above and below said horizontal plane and pivotally connected to arms of the respective bell-crank and manipulating means therefor comprising a segmental gear supported upon one of the bell-crank levers, a pinion suitably jour-

nalled to mesh therewith and an externally arranged hand lever attached to said pinion, substantially as described.

9. In a window regulator, the combination of a window member to be operated, and operating means therefor comprising a supporting and bearing plate adapted to be secured to a window frame member, an actuating pinion suitably journalled in said bearing plate and positioned to the inner side thereof, an operating handle rotatably secured to said pinion and positioned at the opposite or outer side of said bearing plate, a bearing stud mounted upon the supporting member, a lifting lever suitably journalled upon said bearing stud and positioned at the inner side thereof, said lifting lever being provided with a segmental operating gear engaged by said pinion connections from the lifting lever to the window member and a counter-balance spring secured at its inner end to the bearing stud and connected at its outer end to the operating means and said spring being positioned at the outer or operating handle side of the bearing plate, substantially as described.

10. In a window regulator, the combination of a window member to be operated, of an articulated operating lever mechanism comprising reversely arranged bell crank levers, toggle lever connections pivotally connecting one arm of each of the bell crank levers, one of said connections having an

operating lever extension connected to the window member, means to control the movement of said levers in symmetrical angular relation to a fixed plane whereby a rectilinear movement is transmitted to the operating member, said means comprising a movable fulcrum bearing upon one of said connecting members, said bell crank levers being movable above and below their bearing point to extend the movement in reverse angular relation and manipulating means for actuating the operating lever mechanism, substantially as described.

11. In a window regulator, the combination of a window member to be operated, of an articulated operating lever mechanism comprising reversely arranged bell crank levers, toggle lever connections pivotally connecting one arm of each of the bell crank levers, one of said connections having an operating lever extension connected to the window member, means to control the movement of said levers in symmetrical angular relation to a fixed plane whereby a rectilinear movement is transmitted to the operating member, said means comprising a movable fulcrum bearing upon one of said connecting members, and manipulating means for actuating the operating lever mechanism, substantially as described.

Signed at Toledo, in the county of Lucas and State of Ohio, this 29th day of March A. D. 1923.

DORR MILLER.
